SUPPORT FOR A CINEMATOGRAPH, TELEVISION,
STILL CAMERA OR OTHER OPTICAL INSTRU-
MENT

David Wylie Samuelson, Ronald Valentine Prime, and
Brian Frederick Elsden, London, England, assignors to
Samuelson Film Service Limited, London, England

Filed Dec. 23, 1969, Ser. No. 20,612

Term of patent 14 years

Int. Cl. D16—07

U.S. Cl. D61—1

FIG. 1.

Des. 221,900

PAGE 2

Des. 221,900

PAGE 3

FIG. 3.

FIG. 4.

FIG. 1 is a top front perspective view of a support for a cinematograph, television, still camera or other optical instrument showing our new design;

FIG. 2 is a bottom rear perspective thereof;

FIG. 3 is a top plan view thereof, and;

FIG. 4 is a side elevation with the mounting platform tilted in an alternative position.

The broken lines are shown for illustrative purposes only.

We claim:

The ornamental design for a support for a cinematograph, television still camera or other optical instrument, substantially as shown and described.
